(57) **CLAIM**

The ornamental design for a solar-powered spotlight, as shown and described.

DESCRIPTION

FIG. 1 is a top, front perspective view of a solar-powered spotlight showing my new ornamental design in a first position;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a top, front perspective view of the solar-powered spotlight shown in a second position; and,

FIG. 9 is a top, front perspective view of the solar-powered spotlight shown in a third position.

The broken lines in the drawings represent environmental subject matter and form no part of the claimed design. The oblique line shading shown in FIGS. 1, 2, 8, and 9, is used to denote claimed surfaces of the solar-powered spotlight that are transparent.
